DESIGN FOR A COVER OPENING KEY FOR WATERPROOF WATCHES OR SIMILAR ARTICLES

Ernest Loeb, Jamaica, N. Y.

Application September 3, 1943, Serial No. 111,057

Term of patent 14 years

To all whom it may concern:

Be it known that I, Ernest Loeb, a citizen of the United States of America, residing in Jamaica, New York, county of Queens and State of New York, have invented a new, original, and ornamental Design for a Cover Opening Key for Waterproof Watches or Similar Articles, of which the following is a specification, reference being had to the accompanying drawing, forming part thereof, wherein,

Figure 1 is an elevational view of a cover opening key for waterproof watches or similar articles, showing my new design.

Figure 2 is a top plan view thereof, and
Figure 3 is a bottom plan view.

I claim:

The ornamental design for a cover opening key for waterproof watches or similar articles, substantially as shown.

ERNEST LOEB.
